PLIABLE REINFORCED ORNAMENT

Bernhard Berg, New York, N. Y.

Application October 9, 1942, Serial No. 461,484

3 Claims. (Cl. 41—13)

This invention relates to new and useful improvements in pliable reinforced ornaments.

More particularly, the invention contemplates the construction of an ornament as mentioned which is characterized by an ornamenteally shaped felt sheet piece simulating some object, such as a leaf, and pliably reinforced in a certain way. It is proposed to so arrange the reinforcement that the felt sheet may be die cut to have ornamental openings. It is contemplated to characterize the reinforcement by forming the felt sheet piece with a rib portion bent from the material thereof, arranging a pliable wire along said rib portion and encasing the pliable wire and rib portion with a casing formed of stitches.

Still further the invention contemplates numerous modified forms for pliably reinforcing the ornament.

Another object of the invention is the construction of an article as mentioned which is simple and durable, and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a pliable reinforced ornament constructed in accordance with this invention.

Fig. 2 is an enlarged sectional view taken on the line 2—2 of Fig. 1.

Fig. 3 is a fragmentary perspective view of a portion of Fig. 1 with the casing of stitches removed.

Fig. 4 is a plan view of another ornament constructed in accordance with another form of this invention.

Fig. 5 is a fragmentary enlarged sectional view taken on the line 5—5 of Fig. 4.

Fig. 6 is an elevational view of Fig. 5 with the casing of stitches removed.

Fig. 7 is a fragmentary perspective view of a portion of a pliable reinforced ornament constructed in accordance with another form of this invention.

Fig. 8 is another fragmentary perspective view of a portion of another pliable reinforced ornament constructed in accordance with still another form of this invention.

The pliable reinforcement ornament, in accordance with the form of the invention illus-

trated in Figs. 1—3, includes an ornamenteally shaped felt sheet piece 10 simulating some object, such as a leaf, and being formed with die cut openings 11 or other ornamental elements. This felt sheet piece 10 has a rib portion 12 formed by bending upwards a portion of material thereof. A pliable wire 13 is extended along one side of the rib portion 12. A casing 14 of stitches encases the rib portion 12 and the wire 13 and simulates the petiole of the leaf.

The ornament may be used on ladies' hats, coats, dresses, etc. A feature of the new leaf resides in the fact that it may be bent to assume various wavy and other shapes, and the pliable wire 13 will hold the leaf of the ornament as shaped.

In Figs. 4—6 a modified form of the invention is disclosed which distinguishes from the prior form in several respects. More specifically, this pliable reinforced ornament comprises an ornamenteally shaped felt sheet piece 15 having a rib portion 16 bent from the material thereof. A single long strand of pliable wire 17 is extended along one side of the rib portion 16. A plurality of short lengths of pliable wire 18 are extended along the other side of the rib portion 16. A casing of stitches 19 encases said rib portion 16 and said pliable wires 17 and 18.

A feature of this ornament resides in the fact that at the adjacent ends of the short lengths of pliable wire 18, the leaf will be more readily bendable and slightly more flexible than at other areas which would require bending both the wires 17 and 18.

In Fig. 7 another form of the invention has been disclosed which is very similar to the first form distinguishing in the fact that the pliable wire 13 is located within the rib portion 12. The casing of stitches 14 encases the rib portion 12 and this indirectly encases the pliable wire 13.

In Fig. 8 another modified form of the invention is shown which is similar to the form shown in Fig. 7, distinguishing in the fact that a continuous pliable wire 17 and a plurality of short strands of pliable wire 18 are located within the bend of the rib portion 12. The casing of stitches 14 engage about the rib portion and hold the wires 17 and 18 in position. At points between the adjacent ends of the wires 18 the ornament will be more readily bendable and flexible than at other points along the rib portion 12 which requires bending of both of the wires 17 and 18.

While I have illustrated and described the preferred embodiments of my invention, it is to be understood that I do not limit myself to the pre-

cise constructions herein disclosed and the right is reserved to all changes and modifications coming within the scope of the invention as defined in the appended claims.

Having thus described my invention, what I claim as new, and desire to secure by United States Letters Patent is:

1. A pliable reinforced ornament, comprising an ornamenteally shaped felt sheet piece having a rib portion bent from the material thereof, a pliable wire extending along one side of the exterior surface of said rib portion, and a casing of stitches encasing said rib portion and said wire.

2. A pliable reinforced ornament, comprising an ornamenteally shaped felt sheet piece in the form of a leaf, having a plurality of openings and a rib portion bent from the material thereof, pliable wires extending along the sides of said rib

portion, and a casing of stitches encasing said rib portion and wires, one of said wires being in the nature of a plurality of short sections in end alignment with each other.

3. A pliable reinforced ornament, comprising an ornamenteally shaped flat felt sheet piece in the form of a leaf, a centrally longitudinally extending rib formed in said sheet piece by bending a longitudinal area of said sheet piece out of the plane of the remainder of the sheet piece, a continuous pliable wire extending along one side of said rib, a pliable wire of separate sections extended along the other side of said rib with said sections being spaced from each other but in end alignment, and means securing said rib and wires together as a unit.

BERNHARD BERG.
